FARROWING HOUSE PEN

Walter Van Zomeren, Pella, Iowa, assignor to Van Rus
Co., Pella, Iowa, a partnership

Filed June 8, 1961, Ser. No. 65,518

Term of patent 14 years

(Cl. D12—2)

FIG. 1

FIG. 3

FIG. 1 is a perspective view of a farrowing house pen showing my new design;

FIG. 2 is a perspective view of the same as seen looking in a direction diagonally opposite the showing in FIG. 1; and

FIG. 3 is an end elevational view of the same looking toward the left in FIG. 1.

I claim:

The ornamental design for a farrowing house pen, substantially as shown.
